A. A. LOCKWOOD

CONCENTRATION OR SEPARATION OF MINERALS

Filed March 26, 1925

INVENTOR:
ALFRED ARTHUR LOCKWOOD
By his Attorneys,
Baldwin Wright

UNITED STATES PATENT OFFICE.

ALFRED ARTHUR LOCKWOOD, OF LONDON, ENGLAND.

CONCENTRATION OR SEPARATION OF MINERALS.

Application filed March 26, 1925. Serial No. 18,422.

To all whom it may concern:

Be it known that I, ALFRED ARTHUR LOCKWOOD, a subject of the King of Great Britain, residing at Woodford Lodge, Mer-
ton, London, SW. 19, England, have in-
vented a new and useful Improvement Re-
lating to the Concentration or Separation
of Minerals, of which the following is a
specification.

10 This invention has particularly but not exclusively for its object the separation of coal and coke from shale and dirt by a dry process.

According to this invention coal, coke or
15 a suitable ore, or the like, is fed on to a re-
ciprocating table which is smooth near to
an end wall thereon, and is or some part of
it brought by the movement of the table
against said wall, so that the constituents of
20 the coal, coke, ore or the like, or some of
them, rebound from the wall to differing
extents.

Under the term "table having an end
wall" it is intended to include a structure
25 which may be narrow and have a second
wall opposite the said wall, so forming a
structure which is more properly termed "a
trough."

Preferably the coal, coke, ore or the like,
30 meets a current of air and this may be ef-
fected by prividing the wall at or near to
the bottom with a recess running the length
of the wall and closing the mouth of the
35 recess by a porous fabric which then forms
the wall. Air under pressure is led into the
passage so formed.

In this case it may be that there is no
physical contact of the particles with the
wall as a layer of air may take the place
40 of the wall.

In one form of carrying out the invention
I provide a longitudinally inclined flat bot-
tomed tray or trough and impart to it a
transverse to and fro motion and also pro-
45 vide at the outlet of the trough a guide set
to separate the constituents according to the
extent of their rebound.

The angle at which the wall producing
the rebound is set with reference to the di-
50 rection of the movement of the trough will
vary according to the material treated, and
preferably provision is made for easily
varying the angle of the trough.

Although the invention is particularly
55 adapted for separating coal where it is ad-
vantageous not to wet it the process may be

applied to wet separation whether of coal,
coke, an ore or the like.

The invention is illustrated in the accom-
panying drawing, in which Figure 1 is a 60
side elevation of a separating table in ac-
cordance with this invention, Figure 2 is a
plan, and Figures 3 and 4 are respectively
sections on the line 3-3 and 4-4 of Fig-
ure 2. 65

Referring to the drawing, 1 is the sepa-
rating tray or trough, 2 the end wall there-
of, and 3 a feed hopper. Trough 1 is given
an incline such that dry material fed on to
it from hopper 3 will of itself with some
70 mineral or when kept in motion with other
material travel down the trough; trough 1
is moreover given a reciprocating movement
by any well known means such that wall 2
is moved parallel to itself. 75

4 is a partition which prevents material
from the hopper coming on to the table
proper until it is spread out by the recipro-
cation of the trough and approaches the
neighbourhood of wall 2, where, as more
80 clearly seen in Figure 3, it passes beneath
an adjustable gate 4'; as illustrated more
clearly in Figure 4, wall 2 is cut away to
form a recess 2', the wall proper consisting
of a strip of wire gauze 2"; 5 is a pipe lead-
85 ing compressed air into the channel thus
formed.

6 is an adjustable guide at the outlet end
of the trough to separate the constituents
90 nearest wall 2" from those further away,
while a further separation may be effected
by the provision of a gate 7 and orifices 7'
formed in the inclined side wall 8 through
which middlings pass. 95

9 are riffles or their equivalent which
may be provided when the material treated
is apt to cake. 10 is a pivot, 11 a pin and
12 a slot provided on the upper surface of
the table support whereby the inclination
100 of the wall 2 with reference to the recipro-
cating member can be varied.

The apparatus works as follows, it be-
ing supposed that dry coal of a size vary-
ing from $1\frac{1}{4}$ inches to the finest dust is
105 the material to be treated:

The trough (unless specially built for
treating the particular product) is adjust-
ed for wall 2 to be at its most effective
angle and given the requisite incline, so
that the coal travels down the trough when
kept in movement. Coal passing out of
110 hopper 3 is fed forward and passes out be-

neath gate 4' and during its travel down the trough is by the reciprocation of the trough fed towards wall 2, it being assumed that compressed air is not employed; a separation into its lighter and heavier constituents is effected by the reciprocation of the trough, and this separation is enhanced by the impact of the particles against wall 2 as the extent of the rebound of the particles is dependent on their specific gravity. The dirt passes away through the gap between guide 6 and the wall of the trough, while the cleaned coal comes against guide 6 and travels along the inclined side 8; if desired a further separation may take place through orifices 7', the clean coal passing away when it reaches the end of wall 8.

When compressed air is employed the action is precisely the same but as above set out it might be possible with a sufficient pressure of air for the cushion of air thus produced to act as the wall to produce the rebound.

Also it may be desirable to add a certain quantity of the larger portion of previously cleaned coal, while when the coal is all of a coarse size it may be desirable to add a proportion of a finer coal.

Although the table illustrated is designed for dry separation, it may also be used for wet separation, with the addition of a suitable water supply.

It is obvious that there may be a suitable number of troughs arranged in parallel and reciprocated together or a suitable number of troughs inclined alternately in opposite directions and working in series.

What I claim is:—

1. A process of treating material which comprises supporting the same on a smooth surface, subjecting the same to an agitation adapted to cause travel of the material in two directions, and subjecting the material to an air blast substantially parallel to the supporting surface and opposed to one direction of travel of the material, thereby separating the material into different classes.

2. In apparatus for treating minerals, the combination with a table, of a wall thereon, a smooth operative surface near to

said wall, means for reciprocating the table such that the wall moves in a direction parallel to itself, and means for causing a current of air to pass out substantially at right angles to said wall. 55

3. In apparatus for treating minerals, the combination with a table, of a wall thereon, a smooth operative surface near to said wall, means for inclining the table such that one end of said wall is at a higher level than the other, means for reciprocating the table such that the wall moves in a direction parallel to itself, and means for 60 causing a current of air to pass out substantially at right angles to said wall. 65

4. In apparatus for treating minerals, the combination with a table, of a wall thereon, a smooth operative surface near to said wall, obstructions situated at a distance from said wall, means for inclining the table such that one end of said wall is at a higher level than the other, means for reciprocating the table such that the wall 70 moves in a direction parallel to itself, and means for causing a current of air to pass out substantially at right angles to said wall. 75

5. In apparatus for treating minerals, the combination with a table, of a wall thereon formed of an air permeable material having behind it a layer of air, a smooth surface near to said wall, means for inclining the table such that one end of the said wall 80 stands at a higher level than the other end, and means for reciprocating the table such that the wall moves in a direction parallel to itself. 85

6. In apparatus for treating minerals, the combination with a table bounded at one end by a wall and so inclined that one end of the wall is at a higher level than the other end, a smooth operative surface near to the said wall, means for reciprocating the table such that the wall moves parallel to itself, and means for varying the angle of the wall with respect to the reciprocating member operating the table. 90

In testimony that I claim the foregoing as my invention, I have signed my name this 11th day of March, 1925. 95

ALFRED ARTHUR LOCKWOOD.
